[57] **CLAIM**

The ornamental design for a combined automobile splash guard and display unit, as shown and described.

DESCRIPTION

FIG. 1 is a perspective view of a combined automobile splash guard and display unit showing our new design mounted on the left rear of an automobile; which is shown in broken lines of or illustrative purposes only and forms no part of the claimed design,

FIG. 2 is an enlarged front elevation view thereof;

FIG. 3 is an enlarged left side elevation view thereof;

FIG. 4 is an enlarged right side elevation view thereof;

FIG. 5 is an enlarged rear elevation view thereof; and

FIG. 6 is an enlarged bottom plan view thereof.
